UNITED STATES PATENT OFFICE.

CECIL B. HARRISON, OF LOS ANGELES, CALIFORNIA, ASSIGNOR TO H. S. CROCKER CO. INC., OF LOS ANGELES, CALIFORNIA, A CORPORATION OF CALIFORNIA.

FOLDABLE POSTING TRAY.

Application filed June 15, 1923. Serial No. 645,558.

To all whom it may concern:

Be it known that I, CECIL B. HARRISON, a subject of the King of Great Britain, residing at Los Angeles, in the county of Los Angeles and State of California, have invented new and useful Improvements in Foldable Posting Trays, of which the following is a specification.

This invention relates to apparatus for facilitating bookkeeping, and more particularly to a holder and tray for bookkeeping leaves or sheets.

An object is to provide a bookkeeping sheet tray of extreme simplicity and of substantial construction and few operating parts. Another object is to provide a bookkeeping sheet tray having an adjustable back and an independently adjustable front, whereby the bookkeeping sheets may be readily sustained in a substantially upright position in either a tightly bound or a loose stack arrangement.

Another object is to provide a bookkeeping sheet tray having a front receiver portion of such length that it will not interfere with the close-up position of the clerk or bookkeeper having access to the sheets in the tray, and an object is to provide an extension part adapted to be applied to the front receiver when the latter is tilted to its lower position so as to effectively support the sheets in an approximately horizontal position.

An object is to provide a tray having an adjustable bottom and to provide said bottom with means for effectively clamping the lower or stub ends of the sheets comprising a stack.

Other objects and advantages will be made manifest in the following specification of an embodiment of the invention illustrated in the accompanying drawings, wherein:

Figure 1 is a perspective of the closed and covered tray.

Fig. 2 is a perspective of the uncovered and opened tray, the front receiver and the back wall being angularly disposed in a position to facilitate "random posting."

Fig. 3 is a perspective of the tray in position for systematic or alphabetic posting.

Fig. 4 is a vertical section from front to rear, with the parts opened for alphabetic posting.

Fig. 5 is a vertical section on the plane 55 indicated by line 5—5 of Figure 4.

The tray of the present invention consists of a lower, box-like part including a bottom 2, end walls 3, and a short, vertical back wall or flange 4; the bottom being provided preferably with rubber pads or feet 6, forming protective devices to prevent marring of a polished surface on which the tray may be placed. Along the front edge of the bottom 2 is a hinge device 7, forming a pivot for a front box portion including a front panel 10, parallel end panels 10^a and a rear flange 10^b of slightly less height than the end panels 10^a. These end panels are each provided with a slot 11, concentric to the axis of the hinge 7, therefore enabling the front box, which will hereinafter be called the "receiver," to be folded from an extended position shown in Figure 3 to an upright position shown in Figure 1.

The receiver 10 is provided with a handle 12 to facilitate the pulling of the same outwardly to the desired position. The slots 11 of the end panels are provided to receive a transverse tie bolt 13, provided in the upper front corners of the end walls 3, one end of the bolt being provided with a wing nut 14, whereby the front receiver 10 can be locked in either a lowered position or a partially open position shown in Figure 2, and in which position the bookkeeping sheets S, Figure 4, are readily accessible.

The tie bolt 13 not only reinforces the end panels or walls 3, but also forms a means for limiting the unfolding of the receiver 10.

Along the top edge of the back portion 4 of the tray extends a hinge device 15, forming a pivotal connection for the adjustable back structure including a rear wall 16, having a short end wall 16^a and a long end wall 16^b, in the present case along the left-hand side of the tray, so that convenient access by the right hand or arm may be had across the short end wall 16^a in access to the bookkeeping sheets.

The end walls 16^a and 16^b are provided with slots 17, concentric with the axis of the hinge 15, and fixed pins or lugs 18 extend into the slots 17 and limit the unfolding movement of the tray back.

Also pivotally mounted on the hinge 15 is an adjustable platform 20, adapted to

swing from the horizontal position to an upwardly inclined position, Figures 2 and 3. The platform 20 is adapted to be automatically lifted to the inclined position as the front receiver 10 is pulled forwardly. The tilting platform 20 has downwardly extending side flanges 20^b which rest on the top edge of the receiver wall 10^b. The front of the platform is provided with a flange 20^b which is provided with an aperture through which extends a demountable crank 21, having a socket end adapted to interlock with a screw 22, rotatively mounted transversely upon the adjustable platform 20. On the screw 22 is a threaded follower 23, having an upwardly extending cross head 24, disposed above the platform 20 and being movable forwardly and rearwardly along the same as the screw 22 is rotated by the crank 21. The platform is slotted at 20' to provide clearance for a portion of the follower 23, to which the cross head 24 is attached.

At the rear portion of the platform 20 is an upwardly projecting abutment or flange 25, and between this and the face of the cross head 24 the bookkeeping sheets S are adapted to be deposited in an upright position in a stack and firmly clamped when the cross head 24 is forced down by the screw 22 against the lower stub ends of the sheets.

The tray embodying the above details is adapted for efficient use in accordance with the different systems or practices in vogue in making entries from bookkeeping sheets S. In some cases, a systematic or alphabetic bookkeeping system is practiced, and in other instances a random posting may be followed.

The alphabetic system is one in which the sheets S are adapted to be pulled from the upright stack when the binder or cross head 24 is sufficiently released to allow the sheets to be picked in groups, which groups are bodily shifted to and laid face down upon the receiver 10, as shown in lowered position in Figure 4. The tray is of sufficient width to permit the posted leaves or sheets to be offset in the usual manner when deposited in the receiver 10.

In the random posting system, the receiver is fastened in an upstanding position, Figure 2, after the follower 24 is backed off enough to release the sheets in the stack on the platform 20. Then the sheets are toppled forwardly and the desired sheets upon which entries are to be made are picked at random through the stack, which is not broken, as is the practice in alphabetic posting, when groups of the leaves are abstracted from the upright stack and laid upon the receiver 10.

When the tray is not in use, its contents are protected by a removable top or cover 28, adapted to telescope down upon the vertically adjusted receiver and back box structure as shown in Figure 1.

When it is desired to use the tray, it is only necessary to lift the cover 28 off and out of the way and practically in a concurrent action, pull the front receiver forward and throw the back box structure rearward to the maximum degrees at which they will repose. This action instantly exposes the stack of sheets S for access. The sheets are normally fastened securely between the clamping follower 24 and the fixed abutment 25. Before pages or sheets S can be removed, the clamping follower 24 is retracted by rotation of the screw 22, when the crank 21 is applied and turned. While the sheets are firmly locked or clamped in tray they can, at the same time, be readily fingered in pulling one after the other to expose practically the full front of each sheet. The receiver is preferably provided with a detachable extension or false bottom 29, used when the receiver is extended to its lowermost position, Figure 4. The removable bottom 29 has interlocking hooks 29^a to enter apertures 30 provided therefor in the lower portion of the back panel 10^b of the receiver.

When in upright position of the parts, the receiver bottom 29 may be removed and stored within the tray. The receiver 10 is preferably of such depth or height from front to rear or top to bottom as to provide for ready access over its upper edge when the parts are set in random posting position, Figure 2.

Further embodiments, modifications and variations may be resorted to within the principle of the invention.

What is claimed is:

1. A bookkeeping sheet posting tray comprising a base-forming structure, having a bottom, end walls, and a short back wall, a receiver hingedly connected to the front of the base structure and adapted to be swung from a vertical to a forwardly inclined position, a tilttable back device attached to the back wall, and a platform attached to the tilttable back and interposed above the base structure and between the front receiver and the back device, and upon which sheets stand while in stacked relation to the back device.

2. A bookkeeping sheet posting tray comprising a base-forming structure, a receiver hingedly connected to the front of the base structure and adapted to be swung from a vertical to a forwardly inclined position and having a rear flange, a tilttable back device attached to the rear portion of the base structure, and an adjustable platform interposed above the base structure and between the front receiver and the back device, and adapted to rest upon the rear flange, and upon which sheets stand while in stacked relation to the back device.

3. A bookkeeping sheet posting tray com-

- prising a base-forming structure, a receiver hingedly connected to the front of the base structure and adapted to be swung from a vertical to a forwardly inclined position, a 5 tilttable back device attached to the rear portion of the base structure, and a platform interposed above the base structure and between the front receiver and the back device, and upon which sheets stand while in stacked 10 relation in the back device, said platform being automatically raised and lowered by the swinging of the front receiver.
4. A bookkeeping sheet posting tray comprising a base-forming structure, a receiver hingedly connected to the front of the base structure and adapted to be swung from a vertical to a forwardly inclined position, a 15 tilttable back device attached to the rear portion of the base structure, a platform interposed above the base structure and between the front receiver and the back device, and upon which sheets stand while in stacked 20 relation in the back device, and a sheet clamping means provided on the platform.
5. A bookkeeping sheet posting tray comprising a base-forming structure having a solid bottom and a short back wall, a receiver hingedly connected to the front of the 25 base structure and adapted to be swung from a vertical to a forwardly inclined position, a tilttable back device attached to the back wall, a platform interposed above the bottom and between the front receiver and the back device, and upon which sheets stand while in stacked 30 relation in the back device, and means for limiting the unfolding movements of the receiver and the back device.
6. A bookkeeping sheet posting tray comprising a base-forming structure, a receiver hingedly connected to the front of the base 35 structure and adapted to be swung from a vertical to a forwardly inclined position, a tilttable back device attached to the rear portion of the base structure, a platform interposed above the base structure and between the front receiver and the back device, and upon which sheets stand while in stacked 40 relation in the back device, and means for securing the front receiver in various angular positions according to the posting method being employed.
7. A bookkeeping sheet posting tray comprising a base-forming structure, a receiver hingedly connected to the front of the base structure and adapted to be swung from a vertical to a forwardly inclined position, a tilttable back device attached to the rear portion of the base structure, and a platform interposed above the base structure and between the front receiver and the back device, and upon which sheets stand while in stacked 45 relation in the back device, the platform being tilttable upon the axis of the back device.
8. A bookkeeping sheet posting tray comprising a base-forming structure, a receiver hingedly connected to the front of the base structure and adapted to be swung from a vertical to a forwardly inclined position, a 50 tilttable back device attached to the rear portion of the base structure, and a platform interposed above the base structure and between the front receiver and the back device, and upon which sheets stand while in stacked 55 relation in the back device, the platform being tilttable upon the axis of the back device.
9. A bookkeeping sheet posting tray comprising a base-forming structure, a receiver hingedly connected to the front of the base structure and adapted to be swung from a vertical to a forwardly inclined position, a tilttable back device attached to the rear portion of the base structure, and a platform interposed above the base structure and between the front receiver and the back device, and upon which sheets stand while in stacked 60 relation in the back device, the platform being tilttable upon the axis of the back device.
10. A bookkeeping sheet posting tray comprising a base-forming structure, a receiver hingedly connected to the front of the base structure and adapted to be swung from a vertical to a forwardly inclined position, a tilttable back device attached to the rear portion of the base structure, and a platform interposed above the base structure and between the front receiver and the back device, and upon which sheets stand while in stacked 65 relation in the back device, the front portion of said platform being supported upon a part of said receiver so as to be raised and lowered thereby and therewith.

In testimony whereof I have signed my name to this specification.

C. B. HARRISON.
